UNITED STATES PATENT OFFICE.

EMIL HARTMANN, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

PIVOTED-TONGUE BUCKLE.

1,072,717.

Specification of Letters Patent.

Patented Sept. 9, 1913.

Application filed August 26, 1912. Serial No. 717,143.

To all whom it may concern:

Be it known that I, EMIL HARTMANN, a citizen of the United States, residing at Baltimore, in the State of Maryland, have invented a certain new and useful Improvement 5 in Pivoted-Tongue Buckles, of which the following is a full, clear, and exact description.

The invention consists of a buckle having a frame with side flanges and inside pivot 10 bearings, and a tongue pivoted in these bearings beneath the frame and slotted for the passage through it of the strap to be fastened and so disposed with relation to the adjacent end of the frame as to grip the 15 strap between the edge forming the inner boundary of the slot and the adjacent inner edge of the nearer end bar of the frame, the tongue at all times of use being substantially within the boundary lines of the frame, as 20 I will proceed now more particularly to set forth and claim.

In the accompanying drawings, illustrating 25 the invention, in the several figures of which like parts are similarly designated, Figure 1 is a top plan view. Fig. 2 is a bottom plan view. Fig. 3 is a longitudinal section. Fig. 4 is a longitudinal section with the straps in position of use. Fig. 5 30 is a partial side elevation, and Fig. 6 is a partial longitudinal section, showing the pivoted tongue hanging down, as it does when unsupported. Fig. 7 is a top plan view of the pivoted tongue detached.

The buckle frame may be of any approved 35 design, and in the present illustration it consists of the side bars 1, end bars 2 and 3, and the cross-bar 4, the latter preferably being depressed so as to receive the anchoring 40 strap 5 as shown in Fig. 4, without any undue projection from the buckle. The sides 1 are made with the backwardly extending longitudinal flanges 6.

Pivot bearings 7 extend backwardly from 45 the inner edges of the sides 1, and these bearings are perforated transversely to receive the pivots or journals 8 of the pivoted tongue 9. This tongue is made with a transverse opening or slot 10, having a substantially 50 straight strap-gripping edge 11, and a backwardly turned finger-piece 12.

The pivot bearings 7 in a preferred construction are of substantially the depth of

the side flanges 6, or of no greater depth than these side flanges, so as to avoid any 55 projection from the back of the buckle. These pivot bearings are located between the cross-bar and the end bar 3.

The pivoted tongue has its greatest width slightly less than the distance between the 60 side flanges, and so as to fit easily within these side flanges when the buckle is packed and also when it is in use. The tongue is cut away between the widest portion and the pivots 8 so as to swing clear of the pivot 65 bearings, and, as shown in Figs. 5 and 6, this tongue hangs straight down from its bearings when otherwise unsupported.

The relation of the edge 11 of the tongue and the adjacent edge 13 of the end bar 3 70 is such that, as shown in Fig. 4, when the end 14 of the strap to be fastened, is passed up from the back of the buckle through the opening or slot 10 in the tongue and over the tongue toward the other end of the 75 buckle, the strap will be gripped between these edges. The finger-piece or finger-hold 12 puts a bight in the strap which serves to accentuate the hold of the tongue on the strap, as indicated in Fig. 4. It is to be 80 noticed, also, that the tongue is arranged wholly at the back of the frame and is wholly within its outlines or profile; that the adjacent edges 11 of the tongue and 13 of the frame come very close together, the 85 former just below the latter and nearer the transverse center of the frame, thereby insuring the gripping of the strap no matter how thin it may be; and that while the hold on the strap is strengthened by increase of 90 strain, the tongue responds instantly to the slackening of the strain when it is desired to release the strap.

By the construction described, a very simple and efficient pivoted tongue buckle 95 is provided, in which the strap ends may be secured without any material projection; or, in other words, in a flat and slightly manner. As compared with buckles having sliding tongues, this pivoted tongue 100 moving on fixed points and in an arc of a circle, has little or no tendency to wobble, and cannot tilt from side to side and throw the free strap end out of line, but it does and must come up true to the adjacent end 105 bar and grip the strap end entirely across

its width; and further it is very easy to thread, thus adapting the buckle in a special manner for use on wearing apparel.

What I claim is:—

- 5 1. A pivoted tongue buckle, having a frame with sides, side flanges, and end bars, pivot bearings extending backwardly from the inner edge of the sides and adjacent to one end bar and of no greater length than the depth of the side flanges, and a tongue arranged at the back of the frame and whose greatest width is less than the distance between the side flanges and whose leading end lies within the adjacent end bar, and having pivots mounted in said pivot bearings and provided with a transverse opening in its end nearest the adjacent end bar of the frame for the passage of the strap to be fastened, the edge on the tongue forming the inner boundary of said opening coöperating with the inner edge of said adjacent end bar to grip the strap between the tongue and said inner edge of said end bar.
- 10 2. A pivoted tongue buckle, having a frame with sides, side flanges, end bars, and a depressed cross bar to which the strap is
- 15
- 20
- 25

secured, pivot bearings extending backwardly from the inner edges of the sides and adjacent to one end bar and of no greater length than the depth of the side flanges, and a tongue arranged at the back of the frame and of such dimensions as to fit when in use wholly between the side flanges and adjacent end bar and having pivots mounted in said pivot bearings and provided with an opening in its end nearest the adjacent end bar of the frame for the passage of the strap to be fastened, the edge on the tongue forming the inner boundary of said opening coöperating with the inner edge of said adjacent end bar to grip the strap between the tongue and said inner edge of said end bar.

In testimony whereof I have hereunto set my hand this 24th day of August A. D. 1912.

EMIL HARTMANN.
